UNITED STATES PATENT OFFICE.

MILTON W. ARROWOOD, OF WORCESTER, MASSACHUSETTS.

APPARATUS FOR HANDLING POWDERED FUEL. REISSUED

Original application filed March 14, 1923, Serial No. 624,927. Divided and this application filed January 16, 1924. Serial No. 686,506.

This invention relates to the handling of powdered coal and similar material, the present application being a division of my pending application, Serial No. 624,927, filed

5 March 14, 1923.

In feeding powdered coal from hoppers and similar containers, there is a tendency for the coal to pack and form an arch, which interferes with the continuous feeding 10 operation. One of the purposes of my present invention is to prevent this arching and facilitate the uniform feeding of the coal.

The coal in extremely finely powdered condition has a tendency to work into the bearings of the movable parts of the apparatus with the result that they customarily wear rapidly. Another object of this invention, 15 is to dispose the bearings for the movable parts of the apparatus outside the housings 20 in which the powdered coal is confined, so that the coal is practically excluded from the bearings, and their life is thereby much prolonged.

Another purpose of the invention is to provide novel gates for regulating the delivery 25 of powdered coal from the hopper to the mixing apparatus, which gates will prevent escape and leakage of the coal around them, and also to provide means for agitating the 30 fuel to maintain a uniform consistency and uniform weight per cubic unit thereof.

Other objects and advantages of this invention should be readily appreciated as the same becomes better understood by reference 35 to the following description, when considered in connection with the accompanying drawings.

Referring to the drawings:

Fig. 1 is a vertical sectional view through 40 an apparatus embodying my invention;

Fig. 2 is a plan view partially in section of one end of the coal feeding and preliminary mixing apparatus, this figure being taken on the line 2—2 of Fig. 3;

Fig. 3 is a sectional view on the line 45 3—3 of Fig. 2; and

Fig. 4 is a fragmentary view of the mechanism for operating the control gates shown in Figs. 2 and 3.

Referring now to the drawings more in detail, reference character 5 indicates generally the lower portion of a hopper in which the powdered coal is stored and from which it

is fed, this hopper being connected by a closed joint with a tapered trough or receptacle 6 into which the powdered material falls by gravity from the hopper when the control gates are open. The gates 7 and 8, which may be of any preferred form, either

55

curved or flat as shown, are mounted on 60 shafts 9 and 11, respectively, extending through the walls of the hopper base and journaled in outboard bearings. Each shaft is provided outside the hopper with an arm 12 which arms are connected by an operating link 13.

65

It will be manifest that by moving the link 13 longitudinally, rotative movements will be imparted to the shafts 9 and 11, to open and close the gates. It will be observed from Fig. 3 that a stop ledge 70

14 is disposed beneath the outer edge of gate 8 and a similar ledge 15 is disposed over the outer edge of gate 7, whereby the movements of these gates in one direction are limited.

75

The inner edges of the gates overlap when in closed position so that when the gates are positioned as shown in full lines in Fig. 2, the flow of material from the hopper is completely shut off. By rotating the gates in a clockwise direction, 80 viewing Fig. 3, they may be opened or partially opened to any desired degree, as indicated in dotted lines, to permit the requisite flow of material from the hopper. To insure a leak-tight fit, the margin of each 85 gate is preferably provided with a felt sealing strip 16, held in place by a retaining strip 17, which holds the felt strip snugly against the end walls of the passage.

90

The tapered shape of the hopper induces a tendency of the coal in the hopper to form an arch over the gate or gates so that it will not feed uniformly. This objectionable arch, however, may be obviated by suspending within the hopper one or more 95 heavy chains 18 which hang down to a point in proximity to the gate. The constant vibration of such a chain or chains resulting from the operation of the machinery, prevents the objectionable arching of the 100 material in the hopper.

Beneath the gate within the trough 6 and above the bottom thereof, there is mounted a rotatable shaft 19, provided with radially extending spokes or fingers 21, preferably 105 inclined with respect to the longitudinal axis

of said shaft and adapted upon rotation of the shaft to agitate the material passing through the trough, thereby breaking any caked lumps or chunks therein and mixing 5 the same so as to insure an uniformity in the consistency and specific gravity of the fuel, as well as facilitating the feeding of the coal to the feed screw 22 disposed in the bottom of the trough. This feed screw is 10 mounted upon a shaft 23 driven from any suitable source of power, and equipped with a gear 24 which meshes with and drives a companion gear 25 on the shaft 19. In order to prevent leakage of the coal around the 15 shafts and to preclude its entrance as much as possible into the bearings, the shaft 17 is mounted in outboard bearings 26 and 27, and shaft 23 is mounted at one end in an outboard bearing 28 and extends through a 20 stuffing box 29, by which leakage of coal around the shaft is precluded. The gears 24 and 25 are further protected from coal dust by housing 31 surrounding the same, the outer plate 32 of which may be made removable 25 able to permit access to the gears.

The other end of shaft 23 extends through a shell 33 and is journaled in an outboard bearing 34, leakage at this end of the shaft being prevented by a stuffing box 35. Within 30 the shell 33 there is disposed around the shaft a perforated cylinder 36, into which the coal is delivered by the feed screw 22. Air under suitable pressure is delivered to the interior of the cylinder 36 through a supply pipe 37, and this air is mixed with the coal in the cylinder, the mixture being further facilitated by the passage of the coal and air together outwardly through the perforations in the cylinder walls. From shell 35 the mixture of coal and air is discharged 40 through a neck 39 into the mixer proper, or as it is commonly termed, the burner,

This burner may be of any preferred construction but preferably comprises, as shown 45 for illustrative purposes, an outer cylindrical shell 41 in which are disposed a plurality or concentrically arranged shells of progressively decreasing diameter, forming a series 50 of fuel passages alternating with air passages from which air delivered at the intake end 42 of the burner is delivered radially into the mixing passages through apertures 43. The structural details of the burner will 55 not be further elaborated upon as they are fully described and claimed in the parent application previously mentioned.

In the operation of my invention, the hopper gates 7 and 8 having been opened the desired amount, the fuel in the hopper which is 60 prevented from arching by the chain 18, falls by gravity into the trough 6 where it is broken up, agitated and mixed to a uniform consistency by the agitator finger 21. From this trough it is fed by the feed screw 22 into the 65 perforated cylinder 36. Here it is partially

mixed with air, delivered into the cylinder 36 under pressure and upon being discharged outwardly through the perforations in this cylinder it becomes further mixed as it is delivered into the surrounding cylinder 33. 70 From this cylinder 33 it is delivered through the neck 39 into the burner and from thence into the combustion chamber.

The prevention of arching accomplished by the chain or chains 18, the control of the 75 fuel delivery by the gates 7 and 8, and construction and operation of these gates and their capability of effectually preventing leakage around the same, the protection of the bearings in which the rotating shafts operate, the breaking up of the fuel in the trough and the delivery of the same into the preliminary mixing cylinder, and the advantages of these various features should be appreciated without further description. Obviously 80 the structural details illustrated and described may be varied within considerable limits without departing from the essence of the invention as defined in the following 85 claims.

I claim:

1. In an apparatus of the character described, the combination of a hopper, a pair of rotatable vertically swinging intermediate supported control gates mounted beneath said hopper so that adjacent margins of said gates overlap when the gates are in closed position, and abutments at the sides of the hopper against which the outer margins of said gates close. 100

2. In an apparatus for feeding powdered fuel, the combination of a hopper, a trough beneath said hopper, a sealed control gate for controlling the delivery of fuel from said hopper to said trough, a removable carrying section for said gate means in the hopper for preventing arching of the fuel therein, means in the trough for agitating and breaking up the fuel delivered thereto from the hopper, and a feed screw for delivering said fuel from the trough. 110

3. In an apparatus of the character described, the combination of a hopper, a trough beneath said hopper, a control gate for controlling the delivery of material 115 from said hopper to said trough, and means extending along the margins of said gate for sealing the same against leakage, said gate including a plurality of similarly movable sections mounted in the hopper and 120 limited in their movements in opposite directions, the inner edges of the sections overlapping one another.

4. In an apparatus of the character described, the combination of a hopper, a control gate for controlling the delivery of material therefrom, felt sealing strips for preventing leakage around the margins of said gate, said gate comprising a pair of similarly rotatable overlapping sections mount- 125 130

- ed in the hopper, and oppositely acting stop ledges engageable with the sections at the strips to limit the movements of the gates to closed positions.
5. In an apparatus of the character described, the combination of a hopper, a pair of rotatably mounted control gates mounted beneath said hopper so that adjacent margins of said gates overlap when the gates 10 are in closed position, abutments against which the outer margins of said gates close, and sealing strips for preventing leakage around the gates.
6. In an apparatus of the character described, the combination of a hopper, a rotatable control gate mounted in outboard bearings beneath said hopper, abutment means for limiting the closing movement of
- said gate, and sealing strips for preventing leakage around the gate. 20
7. In an apparatus of the character described, the combination of a hopper, a pair of rotatable gates mounted in outboard bearings beneath said hopper, said gates being adapted to overlap when in closed position, abutments for limiting the closing movements of said gates, and means for preventing leakage around the gates. 25
8. In an apparatus of the character described, the combination of a hopper, and means for controlling the discharge from said hopper, said means comprising a plurality of gates rotatably mounted on horizontal axes and adapted to overlap when in closed position. 30

MILTON W. ARROWOOD.
